(57) **CLAIM**

We claim the ornamental design for a model vehicle bumper assembly, as shown and described.

DESCRIPTION

FIG. 1 is an upper, left, front perspective view of a model vehicle bumper assembly showing our new design;

FIG. 2 is a lower, right, front view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is an upper plan view thereof;

FIG. 8 is a lower plan view thereof; and,

FIG. 9 is a lower, right, rear perspective view of the model vehicle bumper assembly.

In the drawings, the broken lines illustrate portions of the model vehicle bumper assembly that form no part of the claimed design.
